STANCHION FOR CAR TOP LUGGAGE CARRIER

Frederick A. Helm, Detroit, Mich., assignor to Helm Accessories, Inc., Detroit, Mich., a corporation of Michigan

Filed May 24, 1962, Ser. No. 70,269

Term of patent 14 years

(Cl. D14—27)

FIG. 1

FIG. 2

FIG. 3

FIG. 4

FIG. 1 is a side elevation of a stanchion for a car top luggage carrier embodying my novel design.

FIG. 2 is a side elevation taken from the opposite side of FIG. 1.

FIG. 3 is a plan view.

FIG. 4 is a right end view.

The dominant features of the design reside in the portions shown in full lines.

I claim:

The ornamental design for a stanchion for car top luggage carrier, as shown and described.
